UNITED STATES PATENT OFFICE.

CARL G. OHLSON AND ALFRED E. JUPE, OF YOUNGSTOWN, OHIO.

DEFORMED REINFORCING BAR FOR CONCRETE.

Application filed September 21, 1921. Serial No. 502,185.

To all whom it may concern:

Be it known that we, CARL G. OHLSON and ALFRED E. JUPE, both citizens of the United States, residing at Youngstown, in the county of Mahoning and State of Ohio, have invented a new and useful Improvement in Deformed Reenforcing Bars for Concrete, of which the following is a full, clear, and exact description.

10 Our invention relates to reenforcing bars for concrete of the type having substantially uniform cross-section and tensile strength.

Heretofore in such type of bars the substantial conformity of cross sectional area has been obtained by shaping the bar so that one portion counteracted another portion at each cross section; for example by a recess in one portion counteracting a projection in another portion, at the same cross section.

Our invention is designed to provide such a bar with a plurality of portions having undulations so arranged that the transverse section of each of said portions is substantially constant throughout the length of the bar: so that each portion is self compensating.

25 A further object of our invention is such an arrangement that the portions referred to in the last preceding paragraph constitute the entire bar, and may be placed in any longitudinal relation to each other, and a bar of substantially uniform cross-section and tensile strength will be produced. That is to say, the portions themselves are self-compensating, and have a substantially uniform transverse cross-sectional area at every point, and therefore the longitudinal relation of the portions with respect to each other is immaterial as far as it affects the sectional area and tensile strength of the bar. This is of importance in making such deformed bars as the rolls used sometimes 35 slightly displace the portions of the bar in the forming thereof.

Further objects of our invention will be apparent upon reading the following description taken in connection with the accompanying drawings which illustrate two embodiments of our invention and in which—

40 Figure 1 is an elevation of the preferred form of bar embodying our invention;

45 Figure 2 is a cross-section on line II—II of Figure 1.

Figure 3 is a view similar to Figure 1 with the bar rotated 90 degrees;

50 Figure 4 is a cross-section on the line IV—IV of Figure 3;

Figure 5 is a side elevation of a different form of bar embodying our invention;

55 Figure 6 is a cross section on the line VI—VI of Figure 5;

Figure 7 is a side elevation of the bar of Figure 5 which has been rotated 90 degrees; and

60 Figure 8 is a cross-section on the line VIII—VIII of Figure 7.

65 Figures 9 and 10 represent some geometrical figures for illustrating the segments used in the bar.

70 Referring to the drawings, the bar shown in Figures 1 to 4 comprises a series of segments 1 and 2 of tores of elliptical cross section. The segments 2 are preferably placed in line with each other, one on each side of the center line of the bar as shown in Figure 2. The segments 1 are similar to the segments 2 but are placed, in the 75 bar shown in Figures 1 to 4, inclusive, 90 degrees from the segments 2 transversely of the bar and are staggered longitudinally of the bar relatively to the segments 2. That is to say, the highest point 3 of each of the segments 2 is equidistant from the highest points 4 of adjacent segments 1 and, likewise, the highest point 4 of each of the segments 1 is equidistant from the highest points of two adjacent segments 2. 80

85 The segments 2 are joined at their ends by ribs 5 which are deepest at their central parts, and similarly, the segments 1 are joined at their ends by ribs 6.

90 The bar shown in Figures 5 to 8, inclusive, is in principle the same as that shown in Figures 1 to 4, inclusive, in that each portion is self compensating; but the segments are of different shape. This bar comprises segments 10 which are opposite each other and segments 11 also opposite each other, the segments 10 and 11 being staggered longitudinally with respect to each other in the same manner as described with respect to segments 1 and 2. The segments 10 have ribs 12 connecting the same, and the segments 11 have ribs 13 connecting the same. The segments and ribs give longitudinal trough-like undulations, and by reason 95 of the peculiar shape of the segments 10 and 11, this trough runs in zig-zag form the entire length of the bar but varies gradually in

extending from the position shown in Figure 6 to that shown in Figure 8 and generally along the line 15 which represents its lowest point.

5 For the purpose of illustration, the bars may be divided as shown by the lines A A and B B. The portion C between the lines A and B has its surface undulations so arranged that that portion is constant in cross-
10 section on any transverse line throughout the length of the bar and the portion C may or may not be the same in cross-sectional area as the portions D, E and F. In other words, the arrangement of the undulations
15 is such that a specified portion of the bars is self-compensating as to its sectional area. By reason of this principle, the sections C, D, E and F may be placed at any longitudinal relation to each other and a bar of uniform
20 total cross-sectional area secured. This feature has a marked commercial value in that the undulations are produced in the bar by means of rolls carrying the configurations. Ordinarily the device is made by passing the
25 same through two rolls, the configuration for one half being on one roll and that of the other half on the other roll. It sometimes happens that the rolls slip with respect to each other, in which event if the total cross-
30 sectional area depended upon an accurate matching of the two rolls a uniform cross sectional bar would not be obtained. With our invention it is immaterial whether the rolls match or not since each specified por-
35 tion of the bar is self-compensating and the resultant of the combination of those portions constituting the bar is therefore uniform quite independently of the longitudinal relation of the portions to each other.
40 If a conic, such as 16 in Figure 10, revolves about an axis in the plane of one of its axes, the body generated in this manner is called a tore. Any part thereof included by a plane and any portion of the curved surface
45 may be called a segment 17 of a tore.

Each segment of our bar has, as shown in Figures 9 and 10, a curved surface which is part of the surface of a tore, and also a flat surface which is produced by a cutting plane. Taking two segments and placing them flat surface against flat surface, and then following at a predetermined distance with two other segments placed flat surface against flat surface and staggered with respect to the first segments, as shown in Figures 1 to 8, we have, with the exception of the longitudinal ribs, the composition of the bar.

The contour of the sections constituting the bar may be anything except a circle or square. The use of segments of square or circular form would not result in a surface having the desirable qualities for such a bar because the surface would not be continuously varying.

Our invention has many advantages resulting from the arrangement described. Some of these advantages are that the bar is substantially uniform cross-section and tensile strength; it is a continuously varying surface as a result of which greater adhesion is effected between the bar and the concrete; the various portions may be at any relative longitudinal position with respect to each other without affecting the uniformity of cross-section and tensile strength of the bar; the segments are of such form that the dies from which they are rolled have an unusually long life in that there are no sharp points or angles to be provided for. Many other advantages will suggest themselves to those skilled in the art. The surface configuration of the bar and the arrangement of the parts are such that the bar as a whole has throughout its length a constant section modulus about any axis at right angles to the longitudinal axis of the bar.

The two bars illustrated in the drawings are merely examples, and we wish it to be understood that we are not to be limited to the particular arrangements shown as many variations may be made in the configuration of the segments and their arrangement with respect to each other which will embody the principles of our invention and vary considerably in appearance from the illustrations shown.

We claim:

1. A deformed concrete reinforcing bar composed of a plurality of portions each constituting less than one-half of the area of the bar, the transverse cross-sectional area of each of said portions being substantially constant throughout the length thereof, said bar having ribs between said portions substantially as described.

2. A deformed concrete bar having a plurality of rows of surface undulations so arranged that the transverse sectional area of that portion lying between planes cutting the center line of adjacent rows is substantially uniform throughout the length of the bar, the undulations varying transversely in curved lines across the face in each said portion, substantially as described.

3. A concrete bar of substantially uniform cross section and tensile strength, composed of a plurality of self-compensating portions, each portion having on every transverse section a curved configuration which varies with respect to a surface of any given outline both longitudinally and transversely in a substantially continuous manner, substantially as described.

4. A concrete bar of substantially uniform cross section and tensile strength, composed of a plurality of self-compensating portions having a curved surface on every transverse section, the section modulus be-

ing approximately the same along the bar, so that the resistance is equal to bending stresses in any radial direction throughout its length, substantially as described.

5 5. A concrete bar of substantially uniform cross section and tensile strength, composed of a plurality of self-compensating portions, each portion having a surface configuration which varies both longitudinally 10 and transversely in a substantially continuous manner, and surface ribs between the said portions, substantially as described.

6. A concrete reenforcing bar of substantially uniform cross section and tensile 15 strength, composed of a plurality of self-compensating portions, having oppositely disposed ribs and oppositely disposed sloping surfaces between the ribs, which merge into the surfaces of the ribs, all of the sur-

faces from beginning to end of each portion varying in angularity to any radial line, substantially as described.

7. A concrete reenforcing bar of substantially uniform cross section and tensile strength, composed of a plurality of self-compensating portions of elliptical cross section varying in diameter from end to end, the greater diameter of adjacent portions being at right angles to each other, each end of each portion overlapping the 20 end of the adjacent portion, while the surface of one portion merges into the surface of the adjacent portion.

In testimony whereof we have hereunto set our hands.

CARL G. OHLSON.
ALFRED E. JUPP.
